UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

CASTING FOR FEEDERS FOR INGOT MOLDS.

Application filed February 15, 1924. Serial No. 693,092.

To all whom it may concern:

Be it known that BLOOMFIELD H. HOWARD and ERNEST J. TURNER, citizens of the United States, residing, respectively, at 5 Washington, District of Columbia, and Pittsburgh, in the county of Allegheny and State of Pennsylvania, have invented certain new and useful Improvements in Castings for Feeders for Ingot Molds, of which 10 the following is a specification.

Our invention relates to improvements in castings for feeders for ingot molds.

The object of our invention is to provide a casting for forming ingot molds of plastic material by forcing the material under pressure through a passage to form a feeder having a large number of walls and ribs on the outer face to correspond with that shown in an application of even date.

20 Another object of our invention is to provide a casting in which the outer walls of the passage are straight and connected by curved walls forming supporting ribs and said ribs connected by curved walls whereby 25 a feeder is formed by a single operation.

A further object of our invention is to provide a specially shaped casting adapted to form a correspondingly shaped feeder and having certain arrangement of parts 30 hereinafter more fully described.

In the accompanying drawings:—

Figure 1 is a vertical sectional view of the lower end of a cylinder having our improved casting attached thereto.

35 Figure 2 is a horizontal sectional view of Figure 1.

Figure 3 is a horizontal sectional view similar to Figure 2 showing an oblong casting.

40 Figure 4 is a horizontal sectional view similar to Figure 3 showing the inner member having straight walls with rounded corners.

45 Referring now to the drawings 1 represents the lower end of the cylinder which is provided with an outwardly extending flange 2 to which is clamped the flange 3 of the outer member 4 of the casting by means of bolt 5. In this form the outer member 50 4 is provided with four oppositely arranged straight walls 6, 7, 8 and 9 the ends of which having connected thereto the outwardly curved walls 10 and 11 connected by an intermediate curved wall 12. The 55 walls 10 and 11 form the supporting ribs on

the outer face of the feeder. The cylinder 1 is provided with a cylindrical member 13 to which is bolted the inner member of the casting by means of bolts 15. The inner member 14 of the casting is provided with four straight walls 16, 17, 18 and 19 beveled as indicated at 20. The walls of the outer member are also beveled as indicated at 21 and whereby the upper end of the passage is flared outwardly to allow the ready entrance 60 of the plastic material into the passage and whereby it is compressed in its passage through the casting.

In the modifications in Figure 3 we have shown an oblong casting constructed exactly 70 like that shown in Figure 2 and like reference numerals indicate like parts.

In Figure 4 we have shown the outer member the same as shown in Figure 2 and like numerals indicate like parts, while the inner 75 member 14 has rounded corners 22.

Having thus fully described our invention what we claim is:—

1. A casting for feeders for ingot molds, comprising an outer member having four 80 oppositely arranged straight walls connected by curved walls.

2. A casting for feeders for ingot molds, comprising an outer member having four oppositely arranged straight walls connected 85 by curved walls, and an inner member.

3. A casting for ingot mold feeders comprising an outer member having four oppositely arranged straight walls connected at the corners by curved walls and an inner 90 member having four straight walls.

4. A casting for ingot mold feeders comprising an outer member having four opposite straight walls connected by three outwardly curved walls and an inner member 95 having four oppositely arranged parallel straight walls.

5. A casting for feeders for ingot molds comprising an outer member having four oppositely arranged straight walls connected 100 to the ends of each wall and outwardly curved walls connected by an outwardly curved wall arranged in a different arc of a circle and an inner member having four straight walls oppositely arranged and parallelled with the straight walls of the outer member.

6. A casting for feeders for ingot molds comprising an outer member having four oppositely arranged straight walls and out- 110

wardly curved walls arranged at the end of each of the straight walls and connected by a curved wall arranged in a different arc of a circle from the first mentioned curved walls and an inner member having four oppositely arranged straight walls.

7. A casting for feeders for ingot molds comprising an outer member having four oppositely arranged straight walls and out-

wardly arranged straight walls and outwardly curved walls arranged at the end of each of the straight walls and having an inner member with straight side walls rounded at the corners.

In testimony whereof we affix our signatures.

BLOOMFIELD H. HOWARD.
ERNEST J. TURNER.
